UNITED STATES PATENT OFFICE.

SVEN THEODOR NELSON, OF OAK PARK, ILLINOIS, ASSIGNOR TO SULLIVAN MACHINERY COMPANY, A CORPORATION OF MASSACHUSETTS.

HEAT-EXCHANGE DEVICE.

Application filed June 27, 1922. Serial No. 571,158.

My invention relates to heat exchange devices.

An object of my invention is to provide an improved heat exchange device. Another object of my invention is to provide improved means for cooling in an improved manner the air passing from the low pressure to the high pressure cylinder of a multi-stage compressor. A further object of my invention is to provide an improved intercooler adapted to be manufactured at small expense and one which at the same time makes it possible to maintain a high rate of heat exchange with resultant efficiency of the compressor. Another object of my invention is to provide improved mountings for intercooling means wherein air tight joints are provided and all tendency of the intercooler to become air bound is effectually overcome. These and other objects of my invention will, however, hereinafter more fully appear.

In the accompanying drawings I have shown for purposes of illustration one form 25 which my invention may assume in practice.

In these drawings,—

Fig. 1 is a side elevation of a compressor equipped with my improved form of intercooler, the intercooler casing being shown in 30 section to facilitate illustration.

Fig. 2 is a detail end elevation of the intercooler showing the cooling fluid connections, the cooling elements within the casing being indicated in dotted lines.

Fig. 3 is a partial transverse sectional view of the intercooler showing the cooling elements within the same, one of the elements being broken away to show its reinforcing means.

Fig. 4 is a detail perspective view of one of the cooling elements and its fluid connections.

Fig. 5 is a transverse section on the line 5-5 of Fig. 2, showing the manner of holding the cooling elements in position in the intercooler.

Fig. 6 is a transverse section on the line 6-6 of Fig. 2.

Fig. 7 is a smaller scale in side elevation of one of the heads.

In the illustrative embodiment of my invention I have shown a compressor of the

well known angle compound type comprising a suitable frame 1 having cylinders 2 and 3 disposed at right angles to each other 55 and pistons 4 and 5 movable in said cylinders, said pistons being connected to a suitable crank shaft 6 adapted to be driven from any suitable source of power and preferably provided with the usual flywheel 7. As 60 usual, the intercooler is located between the low pressure cylinder 3 and the high pressure cylinder 2, the same being shown herein as including a suitable casing 8 connected to the low pressure cylinder through an inlet 65 pipe 9 and to the high pressure cylinder by a discharge pipe 10.

In my improvement it will be observed that the intercooler casing 8 carries within the same a plurality of elongated longitudinally disposed cooling elements 11 which I shall term "pans". As shown, each of these elements extends substantially across the width of the casing 8 at its position of support therein and is provided with opposite faces each adapted to provide a large cooling surface. In the illustrated form of my invention shown herein, these surfaces are shown as flat surfaces although the same may obviously assume other forms. As illustrated, each of these elements 11 is also substantially rectangular and hollow and formed with straight flat sides presenting angles or corners at the junctions with the pan faces, the same preferably being formed 75 of sheet metal suitably riveted or otherwise secured together in such manner as to form a water-tight, rigid, hollow box or unit and then heavily galvanized. In a preferred form, in order to resist any tendency of the 80 pressure to crush these elements or pans, the same are also reinforced with suitable rivets or bolts 12 somewhat after the manner that a locomotive fire box is reinforced. As shown, a plurality of these cooling elements 85 11 is provided, four of the same being shown in this illustrative form of the invention as disposed parallel to one another and superimposed and spaced apart in such a manner as to provide air spaces between their adjacent enlarged cooling surfaces. It will also be seen that as shown in Fig. 1, these elements are staggered, the adjacent ends of alternate pans being preferably disposed

100

closely adjacent to or spaced apart from the opposite ends of the intercooler casing in such a manner as to cause the air entering through the intercooler inlet 9 to pass successively in opposite directions along each pan in traversing the intercooler casing. Thus, it will be observed that when a cooling agent is admitted to the pans, the air to be cooled is caused to flow in a thin sheet over and under each pan in such a manner as to bring it into contact with the surfaces thereof and thus lower the temperature of the air as desired. More specifically, it will be observed that the lowermost element 11 has one of its ends abutting against the head 13 of the intercooler casing and its opposite end spaced apart from the other head 14, while the next element 11 has its opposite ends respectively abutting against the head 14 of the casing and spaced apart from the head 13, the remaining elements being disposed in similar arrangement. It will also be noted that the pipe connections 15 are passed through the heads 13 and 14 and threaded into the ends of the elements 11, and that suitable nuts 16 are screwed tightly against each head to cooperate therewith to form an air-tight joint. Thus it will be observed that the several elements 11 are supported by their connections to the heads and that it is possible by simply connecting the ends of adjacent elements by piping connections 17 to obtain a continuous flow of cooling fluid through the several elements. It will also be noted that in addition to the support furnished by the pipe connections, the cooling elements 11 are each connected to an end strap or support 18 located one at each end of the casing 8, the elements 11 having pins 20 secured thereto at their ends which are received in openings formed in the straps 18. The straps 18 are adapted to support the pans and prevent the same from dropping down into the bottom of the intercooler casing when the heads and pipe connections are removed. It will also be noted that these straps or supports 18 lie in slots which are cut through the center of the ribs or bosses 19 and at right angles to the said ribs (see Figs. 5 and 7). The said ribs are vertically spaced and formed on the heads 13 and 14, in such manner as to form with supports 18 an abutment extending completely across the casing heads (see Fig. 5). The supports 18 are flush with the inner surfaces of the ribs 19. The ends of the pans 11 abut against these abutments as clearly shown in Fig. 6 so as to preclude leakage of air between the ends of the pans and the said abutments. The ends of the straps 18 are made arcuate and engage the inner periphery of the cylindrical casing. In the preferred manner of mounting the pans, best seen in Fig. 3, they extend from wall to wall of the cylindrical casing 8 and the contact between each pan

and the casing walls is on a line along the sharp angles or corners at the sides of the pans forming a tight joint therewith.

Attention is also directed to the fact that in my improved construction the cooling medium is supplied to the different pans at a plurality of points in such a manner as to insure uniform distribution of the cooling liquid therein, the several pipe connections preferably being disposed at opposite sides of the cooling elements as shown. It will also be particularly noted that, as in a preferred construction, the different elements 11 are shown to be disposed at a slight angle relative to the horizontal as, for instance, with their highest points at the left and their lowest points at the right (see Figs. 2 and 3) so that air binding is prevented, the amount of entrapped air being thus minimized due to the fact that the air must be entrapped in the upper left hand corner of each element and cannot exceed a very small amount without coming into the path of the water flowing through the adjacent pipe connection and thus being carried off with the water. It should be further noted that owing to my improved construction no baffle plates, or other baffling means, are required.

In the operation of my improved construction, it will be observed that due to the staggered relation of the cooling elements 11, the air entering the intercooler from the low pressure cylinder through the pipe 9 is caused to engage with the under surface of the lower element 11 and pass along the same to the opposite end thereof, where it is then free to pass in a reverse direction between the upper surface of that element and the lower surface of the next upper element. At the opposite end of this last mentioned element, it is again free to pass upward and in an opposite direction between the upper surface of that element and the lower surface of the next upper element, and at the opposite end of that last mentioned element it is again free to pass upward and along in an opposite direction between the top of that element and the bottom of the top element, and after another upward pass flows between the upper surface of the top-most element 11 and the inner surface of the intercooler casing to the discharge passage 10, through which it passes to the high pressure cylinder. It will also be observed that, due to the construction of the cooling elements 11, a very large cooling surface is produced, and that, by reason of the shape of the elements, the same cause the air to pass in relatively thin sheets above and below the successive elements in its travel through the intercooler casing, thus exposing the air to a very thorough cooling action. It will also be observed that through the provision of these cooling ele-

ments and my improved means for supplying cooling fluid thereto, it is possible to maintain these enlarged cooling surfaces at a relatively low temperature, the water passing in a continuous path from one cooling unit to the other and in a stream which in its passage engages each surface of the six surfaces of each element. By disposing the cooling elements at an angle to the horizontal, it will also be observed that any tendency of the pans to become air-bound is effectually overcome, the air tending to be entrapped being thus forced to keep a position at the upper side of each element, and, through the action of the water flowing through the adjacent outlet, being maintained at the desired minimum, any excess air necessarily being carried off in the water. It will further be noted that either head may be removed and the pans will still be supported in their positions and not drop down, since the straps 18 will continue to support the pans. This will avoid the placing of severe strains on the fluid connections at the ends of the casing remote from the one at which the head was removed. So far as construction and manufacturing costs are concerned, it will also be observed that through my improved construction it is possible to eliminate all necessity for the provision of expensive copper and aluminum tubing and produce an intercooler which may be made with a minimum of labor of ordinary sheet metal. These and other advantages of my improved construction will, however, be clearly apparent to those skilled in the art.

While I have in this application specifically described one embodiment which my invention may assume in practice, it will be understood that this form of the same is shown for purposes of illustration, and that the invention is not necessarily limited to embodiment in this form, the same instead being capable of extensive modification without departing from its spirit or the scope of the appended claims.

What I claim as new and desire to secure by Letters Patent is:

1. An intercooler comprising a casing and a plurality of removable flat rectangular cooling fluid containing members arranged in parallel relation and connected in series, said members dividing the interior of said casing into a plurality of parallel spaces, successive spaces being connected at opposite ends, and means including detachable end supports for said cooling members for permitting the removal of said members longitudinally from said casing.

2. An intercooler comprising a casing, a plurality of parallel hollow substantially flat transversely inclined cooling elements in said casing, and means for connecting said elements in series including cooling fluid

connections arranged adjacent each of the sides of said elements and connecting each intermediate element at one end to an element below it and at its opposite end to an element above it.

3. An intercooler comprising a casing, superimposed substantially flat and hollow cooling elements in said casing, an end of each element abutting an end of said casing to form a substantially tight joint, said cooling elements being connected in series, and connections to said elements for the cooling fluid and also forming a support for said elements in said casing.

4. An intercooler comprising a casing substantially cylindrical in form, substantially flat hollow cooling elements arranged in said casing in parallel relation and at an angle to a horizontal plane in which the axis of the casing lies, the edge of said angle being parallel to said axis, said cooling elements being of less length than the length of said casing, and alternate elements being disposed adjacent opposite ends of said casing, and cooling fluid connections arranged between the higher sides of said cooling elements.

5. An intercooler comprising a casing substantially cylindrical in form, substantially flat hollow cooling elements arranged in said casing in parallel relation and at an angle to a horizontal plane in which the axis of the casing lies, the edge of said angle being parallel to said axis, said cooling elements being of less length than the length of said casing, and alternate elements being disposed adjacent the opposite ends of said casing, cooling fluid connections arranged between the higher sides of the ends of adjacent units, and supporting members located at opposite ends of said casing inside the same and adapted to support the cooling units upon removal of the casing heads.

6. A heat exchange device comprising a casing having heads, a plurality of fluid cooling elements therein dividing the interior of said casing into a single torturous passage for the material to be cooled, and means for supporting said elements in said casing whereby said elements may be retained in their relative positions upon removal of either head from said casing.

7. A heat exchange device comprising a casing, a heat exchange element, a supporting member therefor forming a removable part of said casing, and to which said element is normally secured, and additional means for retaining said element in position operative upon removal of said member.

8. A heat exchange device comprising a casing, a heat exchange element, supporting means therefor forming part of said casing and to which said element is normally secured, additional means for retaining said element in position operative upon removal

of said supporting means, and means permitting cooperation between said retaining means and supporting means to form a substantially leak-proof fit at the end of said element adjacent said supporting means.

9. A heat exchange device comprising a heat exchange element, means associated with said element for temporarily retaining

the same in position in a casing during assembling of the device, and means for permanently supporting said element having parts formed to cooperate with said temporary supporting means. 10

In testimony whereof I affix my signature.

SVEN THEODOR NELSON.
